UNITED STATES PATENT OFFICE.

HENRY H. LAMPERT, OF CHICAGO, ILLINOIS.

BAR SUPPORT.

Application filed February 2, 1927. Serial No. 165,372.

This invention relates to bar supports and spacers and in its principal embodiment is applied to devices for supporting reinforcing bars used in the construction of concrete roads. Bar supports and spacers of this general class usually include a rod having a pin portion adapted to be driven into the ground or other supporting surface and a spacing arm extending transversely thereto for spacing the reinforcing bars from the sides of the mold.

The main objects of this invention are to provide a bar support and spacer of this kind having an improved form of hanger for supporting the reinforcing bar; to provide improved means for movably mounting the hanger on the supporting rod so as to facilitate laying of the reinforcing bars; and to provide improved means for locking the hanger to the rod.

An illustrative embodiment of this invention is shown in the accompanying drawing, wherein:—

Fig. 1 is a perspective of a bar support in its elevated position prior to driving the pin into the ground, part of a side mold being also shown and a reinforcing bar being shown in dotted outline.

Fig. 2 is a similar view, showing the pin driven into the ground.

Fig. 3 is an enlarged plan of the device, part of the spacing arm being broken away.

Fig. 4 is a fragmentary side elevation of the same, part of the hanger being shown in section.

Fig. 5 is a transverse section of the pin, the view being taken on the line 5—5 of Fig. 4 and omitting the hanger.

Fig. 6 is a perspective of the hanger.

Fig. 7 is an enlarged transverse section, taken on the line 7—7 of Fig. 2.

Fig. 8 is a fragmentary side elevation of the part shown in Fig. 7.

In the form shown, the improved bar supports are used for supporting reinforcing bars 1 disposed horizontally and embedded in the concrete a uniform distance above the ground 2. Certain of the bar supports, which support the outer rows of bars, are provided also with means for spacing the outer rows a uniform distance from the vertical side walls 3 which form the molds for the sides of the road.

In the form shown, the device comprises a supporting member 4 having a pin portion

5 and a spacing arm 6 extending at substantially right angles to each other and arranged to support a hanger 7, which is adapted to support the reinforcing bar.

The supporting member 4 preferably is made of wire of heavy gage which possesses the essential rigidity and which may be bent readily to the desired form.

The hanger 7 preferably comprises a sheet metal stamping having an upstanding flange 8 slidably engaging the arm 6 and a base part 9 adapted to embrace the pin 5. Formed in the flange 8, is an aperture 10 through which the arm 6 extends. Axial movement of the hanger 7 along the arm 6 is limited by shoulders 11 struck out from the arm. The base part 9 is bifurcated to provide a slot 12, for receiving the pin 5, and a pair of fingers 13 adapted to embrace the pin. Projecting inwardly from one of the fingers 13, is a shoulder 14 adapted to secure the hanger against accidental withdrawal from the pin 5. The width of the slot 12, at the shoulder 14, is less than the thickness of the part of the pin 5 which is embraced by the fingers 13, so as to necessitate a slight springing of the resilient fingers 13 in forcing the shoulder 14 past the pin to interlock the hanger and supporting member.

Struck out from the pin 5, are shoulders 15 adapted to support the outer end of the hanger base 9, so as to secure the hanger against sagging under the weight of the reinforcing bar.

Embracing the pin portion 5, is a flat bearing plate 16 having an aperture 17 through which the pin extends. Struck out from the pin 5 on opposite sides of the plate 16, are shoulders 18 for securing the plate against axial shifting. The bearing plate 16 is spaced from the hanger 7 the distance which it is desired to space the reinforcing bars above the ground or other supporting surface.

In operation, before the supports are driven into the ground, one of the supports may be used as a marker or gage for marking a line in substantially parallel spaced relation to each of the side molds 3, along which the outer rows of supports are to be driven. In using a support as a gage, it is held in one hand in a plane substantially perpendicular to the mold, with the arm 6 disposed horizontally in sliding engagement with the mold and the pin 5 in engagement with the

surface which it is desired to mark. The device is then moved along the mold to mark the line on the ground.

The supports are then set up in spaced 5 relation along the line, with the arms 6 engaging the mold. After the pins 5 have been driven into the ground, the reinforcing bar is lifted into engagement with the bights of the supporting members 4 and the hangers 10 7 are then shifted into position for supporting the bars. With this improved construction and arrangement of parts, the reinforcing bars may be laid on the ground preparatory to setting the supports and then merely 15 lifted to the hangers after the pins 5 have been driven into the ground.

Although but one specific embodiment of this invention has been herein shown and described, it will be understood that numerous 20 details of the construction shown may be altered or omitted without departing from the spirit of this invention as defined by the following claims.

I claim:

25 1. A device of the class described comprising a supporting member having two portions disposed transversely to each other to form a bight, and a hanger adapted to support a bar in said bight, said hanger having a part 30 slidably supported on one of said portions and another part movable into and out of interlocking engagement with the other portion by the axial shifting of said hanger longitudinally of said one portion.

35 2. A device of the class described comprising a supporting member having two portions disposed transversely to each other to form a bight, a hanger adapted to support a bar in said bight, said hanger having a part 40 slidably engaging one of said portions and another part adapted to be moved into and out of interlocking engagement with the other portion by the axial shifting of said hanger longitudinally of said one portion, 45 and means on said other portion adapted to support said other part of the hanger.

50 3. A device of the class described comprising a member having a portion adapted for upright support and a second portion disposed transversely thereto to provide a bight, a hanger adapted to support a bar in said bight, said hanger having sliding engagement with one of said portions and adapted for interlocking engagement with the other, 55 and a shoulder on said upright portion adapted to support a part of said hanger.

4. A device of the class described comprising a member having a portion adapted for upright support and a second portion

disposed transversely thereto to provide a 60 bight, a hanger adapted to support a bar in said bight, said hanger having sliding engagement with said second portion and adapted for interlocking engagement with said upright portion, and a shoulder on said 65 upright portion adapted to support a part of said hanger.

5. A device of the class described comprising a member having a portion adapted for upright support and a second portion disposed transversely thereto to provide a bight, 70 a hanger adapted to support a bar in said bight, said hanger having sliding engagement with said transverse portion and having a bifurcated part adapted to embrace said upright portion, and a shoulder on said upright portion adapted to support the bifurcated part of said hanger.

6. A device of the class described comprising a member having a portion adapted for upright support and a second portion disposed transversely thereto to provide a bight, a hanger adapted to support a bar in said bight, said hanger having a part slidably engaging said transverse portion and another part movable into and out of interlocking engagement with said upright portion by the axial shifting of said hanger relative to said transverse portion, and means on said upright portion for supporting said other part 90 of the hanger.

7. A device of the class described comprising a member having a portion adapted for upright support and a second portion disposed transversely thereto to provide a bight, 65 and a hanger adapted to support a bar in said bight, said hanger having a part slidably supported on said transverse portion and a bifurcated part movable into and out of interlocking engagement with said upright portion by the axial shifting of said hanger longitudinally of said transverse portion.

8. A device of the class described comprising a supporting member having two portions disposed transversely to each other to form a bight, a hanger adapted to support a bar in said bight, said hanger having a part 100 slidably supported on one of said portions and a slotted part movable into and out of interlocking engagement with the other portion, and a shoulder on said slotted part arranged to engage said other portion for securing said hanger against accidental withdrawal from said supporting member.

Signed at Chicago this 31st day of January, 1927.

HENRY H. LAMPERT.
